UNITED STATES PATENT OFFICE

CARL E. KRAMER, OF FAIRVIEW VILLAGE, OHIO, ASSIGNOR TO THE CLEVELAND WROUGHT PRODUCTS COMPANY, OF CLEVELAND, OHIO, A CORPORATION OF OHIO

LADDER JACK

Application filed August 17, 1931. Serial No. 557,545.

This invention relates to ladder jacks and is an improvement over my prior Patent No. 1,578,529 granted March 30, 1926.

The most important feature of the present invention resides in provision of a safety means whereby the probability of accident due to breakage, to persons using the ladder jack embodying the invention, is practically eliminated.

10 Another object of the present invention is to provide a ladder jack which is simple in construction, efficient and inexpensive to manufacture.

Reference should be had to the accompanying drawing forming a part of this specification in which

15 Figure 1 is a perspective view of a ladder and a jack mounted thereon;

Fig. 2 is a top plan view of the jack with portions omitted;

Fig. 3 is a top plan view of the upper part of the jack.

Fig. 4 is a fragmentary side elevational view on an enlarged scale showing the construction embodying the present invention;

Fig. 5 is a top plan view of that shown in Fig. 4.

Referring to the drawing, 1 and 2 indicate side members which at their forward ends are pivoted as indicated at 3 upon a post 4. This post may conveniently be made as a sheet metal member which is folded upon itself to form a T-base 4^a and has upwardly projecting ears which at their upper ends are spaced apart as indicated at 4^b to receive between them a pivoted bar 5. The ends of the side members 1 and 2 are pivoted on the side flanges of the base 4^a.

At the opposite ends of the side members 1 and 2 there are secured U-shaped yokes 6 and 7 which are adapted to pass around the opposite side rails of a ladder. In order that the yokes 6 and 7 may properly engage with the side rails of the ladder, the members 1 and 2 are bent at a slight angle as indicated at 1^a and 2^a and to this bent portion one side of each U-shaped yoke is attached.

In order to prevent the side members 1 and 2 from moving away from the ladder when once mounted thereon, at least one of

the side members is provided with a downwardly extending hook 8 which will extend behind one of the rungs of the ladder and thus position and retain the side members against moving away from the ladder.

55 The bar 5 extends through a slot which is formed in a member 9, which member has pivotally secured to it, two diverging members 10 and 11. These members 10 and 11 at their outer ends are provided with hook-shaped portions which are adapted to extend around the side rails of a ladder and to rest upon one of the rungs of the ladder. The bar 5 is provided with a plurality of notches 5^a and the member 9 engages in these notches 60 and so holds or supports the pivoted ends of the side members 1 and 2.

65 These ladder jacks are in practice used in pairs, each jack being mounted upon one of a pair of ladders which are spaced apart. Between the jacks there extends a platform or plank. The side members 1 and 2 are adapted to receive and support one end of such a platform or plank.

70 When the jack is used as above described 75 the load on the platform or plank and the bending moments incident thereto are transmitted in large part directly to the side rails of the ladder, which portions of the ladder are the strongest portions and will withstand 80 greater stresses and strains than the rung of the ladder could possibly stand.

75 The adjustability of the strap 5 with respect to the member 9 permits the jack to be 85 adjusted with respect to the ladder so as to have the side members 1 and 2 in a substantially horizontal plane and thus provide for different angular positions of the ladder with respect to the wall or smaller object against which the upper end of the ladder is placed.

90 Due to the pivoted construction the jack may be completely folded so that when not in use it will occupy but a limited amount of space.

95 It will be apparent that there can be substantially no side sway to the jack because when the side members 1 and 2 are caused to engage with the side rails of the ladder and the hooks 8 pass over the adjacent rung, the side members 1 and 2 and the ladder form in 100

effect a triangle and a stiff resisting structure.

Additionally the U-shaped members 6 and 7 engage with the side rails very snugly and 5 therefore turning of the members 6 and 7 on the side rails of the ladder is prevented.

In Figs. 4 and 5 there is illustrated the safety means embodying the present invention.

10 The pivoted end of the bar 5 is provided with an arcuate slot 13 in its underside within which is normally disposed the shank or body of a pin or rivet 12 which has its opposite ends rigidly secured to the projecting 15 ears of the post 4.

It will, therefore, be readily seen that should the pivot at the end of the bar 5 become broken or otherwise accidentally disengaged, the end of the bar 5 and the post 4 20 will not become separated due to engagement between the pin 12 and the slotted portion of the bar 5, the load being taken by the pin 12. This construction, therefore, provides a ladder jack which is practically safe, 25 even though portions of the jack should become broken or accidentally disengaged.

While I have described the preferred embodiment of the invention, it is to be understood that I am not to be limited thereto inasmuch as changes and modifications may be 30 resorted to without departing from the spirit of the invention as defined by the appended claims.

Having thus described my invention I 35 claim:

1. A ladder jack comprising a pair of side members flexibly connected at one end so as to be relatively movable at the other, rail engaging members associated with the free ends of 40 said side members, a bar pivotally connected adjacent the connected ends of said side members, rail hook members adjustably connected with the free end of said bar, and interengaging means between the end of said bar and 45 said side members and adapted to support the side member independently of the bar pivot in case of accidental disengagement.

2. A ladder jack comprising a pair of side members flexibly connected at one end so as to be relatively movable at the other, rail engaging members associated with the free ends of 50 said side members, a bar pivotally connected adjacent the connected ends of said side members, rail hook members adjustably connected with the free end of said bar, and a pin and slot connection between the end of 55 said bar and said side members and adapted to support the side member independently of the bar pivot in case of accidental disengagement.

3. A ladder jack comprising a pair of side members, a bracket to which said side members are connected and having a pair of spaced ears, rail engaging members associated with the free ends of 60 said side mem-

bers, a bar pivotally connected to the ears of said bracket, rail hook members adjustably connected to the free end of said bar, and a pin extending between the ears of said bracket and secured thereto, said bar having an 70 arcuate slot in its lower side beyond the pivot therefor and adapted to normally receive said pin therein.

In testimony whereof, I hereunto affix my 75 signature.

CARL E. KRAMER.
